DESIGN FOR A LINK CHAIN FOR A BRACELET OR SIMILAR ARTICLE

Jules Braunstein, Los Angeles, Calif.

Application November 13, 1945, Serial No. 123,672

Term of patent 7 years

(Cl. D45—4)

To all whom it may concern:

Be it known that I, Jules Braunstein, a citizen of the United States, residing at Los Angeles, in the county of Los Angeles and State of California, have invented a new, original, and ornamental Design for a Link Chain for a Bracelet or Similar Article, of which the following is a specification, reference being had to the accompanying drawing, forming part thereof.

Fig. 1 is a top plan view of a link chain for a bracelet or similar article, showing my new design.

Fig. 2 is a side view thereof.

The dominant features of the design reside in the portions shown in full lines in the drawing.

I claim:

The ornamental design for a link chain for a bracelet or similar article, substantially as shown and described.

JULES BRAUNSTEIN.
